Primary Examiner — Karen S Acker

(57)

CLAIM

The ornamental design for an electric pressure cooker, as shown and described.

DESCRIPTION

1. Electric pressure cooker

1.1 Front

1.2 Back

1.3 Left

1.4 Right

1.5 Top

1.6 Bottom

1.7 Perspective

Broken lines showing in reproductions 1.1-1.7 depict portions of the electric pressure cooker that form no part of the claimed design.
